[57] CLAIM

The ornamental design for a trampoline exerciser, as shown and described.

DESCRIPTION

FIG. 1 is a left side elevational view of a trampoline exerciser showing our new design with the right hand side elevational view being a mirror image thereof; FIG. 2 is a front elevational view thereof with the rear elevational view being a mirror image thereof; FIG. 3 is a top plan view thereof; FIG. 4 is a bottom plan view thereof; and, FIG. 5 is a perspective view thereof shown on a reduced scale.

Fig. 1.

*Fig.2.**Fig.3.**Fig. 4.**Fig. 5.*
